UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLER.

1,321,645.

Specification of Letters Patent. Patented Nov. 11, 1919.

Application filed January 4, 1915. Serial No. 410.

To all whom it may concern:

Be it known that I, CHARLES J. KLEIN, a citizen of the United States, residing at Milwaukee, in the county of Milwaukee and State of Wisconsin, have invented new and useful Improvements in Circuit-Controllers, of which the following is a full, clear, concise, and exact description, reference being had to the accompanying drawing, forming 10 a part of this specification.

This invention relates to circuit controllers.

One of the objects of the invention is to provide efficient and improved means for insuring the continuance of certain pre-established circuit conditions during the interruption of another circuit.

A further object is to provide simple and improved means to lock a plurality of reciprocable switch operating members against movement in either direction.

Other objects and advantages will be in part obvious and in part pointed out hereinafter in connection with a description of the accompanying drawing which illustrates a typical embodiment of the invention, and in which—

Figure 1 is a plan view of a multi-switch controller.

Fig. 2 is a view thereof with the cover plate removed.

Fig. 3 is a partial sectional view on line 3—3 of Fig. 1.

Fig. 4 is a sectional view on the line 4—4 of Fig. 1, and,

Fig. 5 is a plan view of a modification of the device with the cover plate therefor removed.

The device shown is a circuit controller particularly designed for automobile lighting and ignition systems. The device is commonly mounted flush in an accessible part of the automobile dash and includes a plurality of snap switches having push and pull operating members and another switch having a pivoted operating member. In practice the push button switches preferably control the automobile lighting circuits while the lever operated switch controls the ignition circuit.

More specifically, a receptacle 1 of insulating material houses a plurality of snap switches having push and pull operating members, 2, 3 and 4 and another switch hav-

ing an oscillating operating member 5. A cross plate 6 extends over and is fixed to the receptacle and is provided with suitable apertures to accommodate the several switch operating members and with holes 7 for receiving screws to attach the device to its support.

Interlocking means is provided to restrain the push button switches against operation while the ignition switch is in open circuit position. Thus the lighting switches are locked against unauthorized operation at all times while the automobile is idle. As illustrated, a stamped metal disk 8 is pivotally secured by a pin 9 to the cross plate 6 and is provided with openings 10 and 11 through which the push buttons 2, 3 and 4 extend. The opening 10 is enlarged at opposite sides of a restricted communicating slot and the opening 11 consists of two connecting openings similar to the one 10. The push buttons are provided with fixed collars 12 movable between the cross plate 6 and a face plate 13 whereby the travel of the operating members is limited. The openings in the rotatable disk 8 have maximum widths to allow the collars 12 to pass freely therethrough and a restricted width to engage the collars and hold the push buttons against operation. For example, when the push button 1 is depressed and the disk 8 rotated (Fig. 3), it is apparent that the button is locked against outward movement. Similarly when the button is pulled to outermost position and the disk rotated the former is locked against depression. Inasmuch as the push buttons 2, 3 and 4 are all arranged for independent operation, the same may be simultaneously locked irrespective of the extreme position of each.

The oscillating switch lever 5 is pivoted through the cross plate 6 and has a polygonal section 14 arranged to interfit a correspondingly shaped opening 15 in a swinging plate 16 resting upon the cross plate 6. Said swinging plate has an extension 17 at one side which is connected by a link 18 with an offset extension 19 of the rotatable disk 8. Thus the oscillating lever 5 controls the position of the disk 8 so that when the ignition switch is operated, the push buttons 2, 3 and 4 are locked or released accordingly. The plate 16 also has an upright lug 20 at its other end which works in an arc-shaped

slot 20^a in the face plate and in which is an aperture 21 to aline with an aperture 22 in a lug 23 on the cross plate 6 when the ignition switch is in open circuit position. 5 Suitable means, such as the shackle of a padlock 24, may be fixed through the apertures 21, 22 to lock the ignition switch against operation and thereby lock the automobile against unauthorized use. At the 10 same time the push button switches controlling the lighting system are also positively restrained by the disk 8 against manipulation.

In Fig. 5 a modified form of the device is 15 shown wherein the ignition switch is mounted intermediate certain of the push button switches. In this embodiment, a pair of locking plates 25 and 26 for the push buttons 2, 3 and 4 respectively are pivotally mounted 20 on the cross plate 6 by pins 27. Said plates are provided with offset extensions 28 disposed toward each other, and a swinging plate 29 controlled by the lever of the ignition switch has opposite extensions 30 overlying the extensions 28. A lost motion connection is provided between the swinging plate 29 and the locking plates 25 and 26. 25 As illustrated, this connection comprises pins 31 on the plate extensions 30 which work in slots 32 in the plate extensions 28. Thus movement of said swinging plate in either direction from its intermediate position imparts pivotal movement to the plates 25, 26 which thereupon lock the push buttons 30 in the manner above set forth. In this 35 form also, the swinging plate 29 is provided with an upstanding lug 33 which works in a suitable arc-shaped opening in the face plate and has an aperture to aline with an aperture on a fixed lug 34 of the cross plate 6, so that the ignition switch may be locked 40

in open circuit position in the manner also above set forth.

What I claim as new and desire to secure by Letters Patent is:—

45 1. In a device of the character described, in combination, a receptacle, a cross plate and a face plate thereon, a switch mechanism within said receptacle having a permanently connected reciprocably acting 50 switch operating member extending through said plates, said operating member having means coöperating with said plates respectively for limiting movement of said operating member in either direction, a second 55 switch mechanism within said receptacle and having a swinging operating member, a pivoted locking disk for said reciprocably acting operating member and a swinging disk movable by said swinging operating 60 member to move said locking disk, said disks being disposed between said plates.

2. In a device of the character described, in combination, a receptacle, a cross plate thereon, a switch mechanism within said 65 receptacle having a push and pull operating member extending through said cross plate, a switch mechanism within said receptacle having a swinging operating member, a face plate for said receptacle, a pivoted locking 70 disk for said push and pull operating member and a swinging disk movable by said swinging operating member to move said locking disk, said disks being disposed between said plates.

75 In witness whereof I have hereunto subscribed my name in the presence of two witnesses.

CHARLES J. KLEIN.
